UNITED STATES PATENT OFFICE.

CARL DANIELSON, OF CHICAGO, ILLINOIS.

HORSESHOE.

1,413,324.

Specification of Letters Patent. Patented Apr. 18, 1922.

Application filed August 27, 1920. Serial No. 406,399.

To all whom it may concern:

Be it known that I, CARL DANIELSON, a citizen of the United States, residing at Chicago, in the county of Cook and State of Illinois, have invented certain new and useful Improvements in Horseshoes, of which the following is a specification.

This invention relates to improvements in horseshoes, and its object is to provide a horseshoe provided with removable heel and toe calks which when worn can be replaced thus saving the shoe frame and prolonging its life indefinitely. A further object is to provide a horseshoe having a rubber heel calk that is vulcanized to a removable plate which plate is removably carried by the shoe frame, the combination providing a shoe that will serve as a shock absorber for the animal wearing it and that will prevent slipping on icy pavements, that will prove a good shoe for muddy roads or for hard pavements, and a shoe that is simple in construction, cheap to manufacture, and efficient and durable in use.

With the foregoing and other objects in view the invention consists in the combination and arrangement of parts to be herein-after fully described, pointed out in the appended claim, and illustrated in the accompanying drawings which form a part of this specification and in which—

Figure 1 is an inverted plan view of my improved horseshoe,

Fig. 2 is a view of the same in side elevation,

Fig. 3 is a plan view of the heel calk removed from the shoe frame,

Fig. 4 is an edge view of Fig. 3, and

Fig. 5 is a section on line 5—5 of Fig. 1. Like reference characters denote corresponding parts throughout the several views.

My shoe comprises the frame 1 the toe of which is formed with the transverse groove 2 which is partly closed by the oppositely disposed spaced lips 3 adapted to ride in the grooves formed in the reduced portion 4 of the toe calk 5, the base of said toe calk riding in the groove 2. The toe calk is formed with a threaded groove to receive the end of the headless screw 6 that extends into a threaded bore 7 in the toe of the frame which

bore opens into the said groove 2, said screw 6 serving to releasably retain the toe calk in position so that the same may be removed and replaced by a new one when worn out or broken.

The rear ends of the frame are recessed to form the reduced portion 8, which portion is formed with a perforation 9 into which a perforation 10 opens which is disposed at right angles to the perforation 9. A rubber heel pad 11 is recessed along its ends 12 and is vulcanized to a metal plate 13, said plate being formed with perforations 14 in its ends, the body portion of said plate extending through and being imbedded in the thickened body portion of the pad 11, the ends of said plate 13 being adapted for disposal upon the reduced portions 8 of the frame 1, said plate being formed upon its ends with the lugs 15 which are disposed in the frame perforations 9, the lug perforations 9^a being threaded to receive the screws 16 that extend through the frame perforations 10. The tread surface 17 of the heel calk bridges the rear end of the frame 1 and affords a superior heel pad for the animal.

When the rubber pad is worn it is removed by removing the screws 16 and then forcing it, together with the plate 13, out of the frame. The plate 13 can be chiseled out of the worn pad and a new pad vulcanized thereto and the same secured to the original frame 1.

What is claimed is:

In a horseshoe, a frame, recessed and perforated heel portions in said frame, a plate removably disposed in the said recessed heel portions, lugs formed integral with said plate and disposed in the perforations of said heels, retaining screws connecting said frame and lugs, and a rubber pad carried by said plate, said pad bridging the spaced ends of the heels of the frame.

In testimony that I claim the foregoing as my own I have hereto affixed my signature in the presence of two subscribing witnesses.

CARL DANIELSON.
